UNITED STATES PATENT OFFICE.

WILLIAM ROSE, OF BROOKLYN, NEW YORK.

BATH SPRAY OR DEVICE.

1,279,006.

Specification of Letters Patent. Patented Sept. 17, 1918.

Application filed March 31, 1917. Serial No. 158,903.

To all whom it may concern:

Be it known that I, WILLIAM Rose, citizen of the United States, and resident of the borough of Brooklyn, county of Kings, city 5 and State of New York, have invented certain new and useful Improvements in Bath Sprays or Devices, of which the following is a specification.

My invention relates to bath-sprays or 10 shower devices for use more particularly in bath tubs.

The objects of my invention, generally stated, are to provide a simple and efficient device of the character specified which may 15 be manufactured at small cost; which may be readily applied to or detached from a standard bath tub fixture; which may be readily adjusted to and held for use in different positions; which affords a full and 20 effective shower without the liability of discharging outside or over the edges of the tub; and which may be used as a container to receive and discharge perfume, liquid soap, &c.

25 To the above and other ends which will hereinafter appear, my invention consists of the features of construction, arrangements of parts and combinations of devices set forth in the following specification and particularly pointed out in the appended claims.

In the accompanying drawing wherein like reference characters designate corresponding parts in the various views,

Figure 1 is a detail perspective view of 35 my device shown attached to the faucet of a bath tub and supported in position for use.

Fig. 2 is a detail top plan view of supporting and adjusting means for the spray head.

Fig. 3 is a detail side view with parts 40 broken away, of the spray head or nozzle.

Fig. 4 is a rear view of the same.

The bath-spray or device of my invention comprises an outlet head indicated as a whole by the reference numeral 1. This head 45 is preferably elliptical in contour as shown and is formed as a hollow receptacle, access to which may be gained through an opening which ordinarily is closed by a detachable cover or cap 2. In the present instance this 50 cover is in the nature of a screw cap threaded at 3 for coöperation with corresponding threads on a nipple which projects from the rear side of the head 1. The opposite broad

side of the head is perforated at 4 to provide outlet openings. When the screw cap 2 is 55 removed access is afforded to the inside of the hollow head in order to clean it or remove any obstructions from the outlet openings. It will likewise be understood that the head 1 is in the nature of a container in 60 which perfume, hard or liquid soap, sea salt or any other suitable material may be introduced when the cap is removed. In use, water passing through the head will become mixed with, or take up, such material, 65 conveying it in a fine spray directly to the body of the user of the device. This is a more economical method of using such materials than to attempt to use the same in the entire contents of the tub.

70 One end of the head is provided with an inlet tube or nipple 5 by which water is conveyed to the head from a bath tub faucet 6 through a flexible tube 7. One end of the tube fits over the nipple 5 and the other end 75 over the outlet of the faucet 6. A collar, strap or band 8 surrounds that end of the tube 7 which is on the nipple 5. The ends of the strap are bent off from the circular portion thereof to form two parallel arms 9 80 which are perforated to receive a headed screw 10. The threaded end of the screw receives a thumb nut 11 which acts as a binding screw to draw the ends of the strap together and tighten the loop thereof on the 85 flexible tube and thus securely bind it to the nipple 5. A corresponding collar, strap or band surrounds that end of the flexible tube which is on the faucet 6 and in a like manner 90 secures the tube to the faucet with the aid of a binding screw. The parts of this second attaching device are designated by the same reference characters as those employed to indicate the corresponding parts of the 95 previously described device, with the addition thereto of the exponent *a*. A supporting arm, bracket, or member 12 is received at one end between the arms 9^a of the strap 8^a and is perforated for the free passage therethrough of the screw 10^a, thus forming 100 a pivotal connection between the member 8^a and the arm 12 by which the latter may be adjusted. When the thumb nut 11^a is tightened it binds the arms 9^a against the arm 12 and holds it in the position to which it may 105 be adjusted around its pivot 10^a. The oppo-

site end of the arm 12 is received in a like manner between the arms 9 of the strap 8, the screw 10 constituting a pivot by which the head may be turned on arm 12. By 5 tightening the thumb nut 11 the head may be held in any position to which it is adjusted around the pivot 10 which connects it to the arm 12. From the foregoing description it will be understood that each of 10 the devices 8 and 8^a performs a two-fold function. Thus, the member 8^a binds the flexible tube to the faucet and firmly supports the spray device on the faucet, permitting a bodily rotative adjustment around 15 the faucet if desired. The member 8^a also provides means for retaining the arm 12 in the position to which it may be adjusted around the pivot 10^a.

The strap 8 in addition to firmly connecting one end of the flexible tube to the spray head connects the head to the arm 12 and holds the head in the position to which it may be adjusted on the arm 12 around the pivot 10. The strap 8 also enables an adjustment of the spray head to be effected around the axis of the nipple 5 if desired. It will be understood therefore that the construction in effect provides a universal joint by which an adjustment of the head to various positions and to various angles may be effected. Ordinarily, however, it is sufficient to provide an adjustment of the head to different elevations and to different angles with reference to the surface of the water in 20 the tub, without turning the head toward the sides of the tub and while it is maintained in the median plane thereof. These adjustments may be readily effected under the conditions mentioned with my device and in 25 some instances without disturbing the adjustments of the binding screws. These adjustments of the head under the conditions specified are advantageous in that it prevents water from being discharged from the 30 spray head over the sides of the tub. The spray-device of my invention has been devised as a whole with this last mentioned object in view and the construction is such that it is difficult at any time to discharge water 35 from the spray over the sides of the tub unless it be deliberately set or adjusted with this object in view.

By forming the spray head elliptical in cross section, I provide an increased flow 40 from the head without incurring the risk of water being projected over the sides of the tub, the shorter diameter of the head being presented crosswise of the tub under all ordinary adjustments of the head.

From the foregoing description it will be 45 understood that by my invention I have provided a construction all parts of which, except the flexible tube, may be made of sheet metal; that the construction comprises but 50 few parts and may be manufactured at small

cost, and that the device is efficient in use and may be readily applied to or detached from bath tub fixtures of standard construction.

It will be understood that certain features 70 may be employed without others and that various changes may be made without departing from the spirit and scope of my invention.

What I claim as new and desire to secure 75 by Letters Patent, is:—

1. A bath-spray comprising an outlet head; a flexible tube adapted to connect said head to a bath tub faucet; and mounting means for detachably and adjustably supporting said head in place, said mounting means comprising an arm pivoted at one end to the outlet head and pivoted at the other end to a member carried by a fixed support. 80

2. A bath-spray comprising an outlet 85 head; a flexible tube adapted to connect said head to a bath tub faucet; and mounting means for detachably and adjustably supporting said head in place, said mounting means comprising a member detachably connected to a fixed support, an arm pivoted at one end to said member and at its other end to said head, means for retaining the arm against pivotal movement on said member in order to hold the arm in the position 90 to which it may be adjusted, and means for holding said head against pivotal movement on said arm so that the head may be held in the position of its adjustment on said arm. 95

3. A bath-spray comprising an outlet 100 head; a flexible tube adapted to connect said head to a bath tub faucet; and mounting means for detachably and adjustably supporting said head in place, said mounting means comprising a band which surrounds the flexible tube and binds it on the faucet, and means carried by said band for adjustably supporting said head on the faucet. 105

4. A bath-spray comprising an outlet 110 head; a flexible tube adapted to connect said head to a bath tub faucet; and mounting means for detachably and adjustably supporting said head in place, said mounting means comprising a band which surrounds the flexible tube and binds it on the faucet, an arm pivoted to said band, a binding screw for holding the band on the faucet and for holding the arm in the position to which it is adjusted around said pivot, and means for connecting the head to said arm. 115

5. A bath-spray comprising an outlet 120 head; a flexible tube adapted to connect said head to a bath tub faucet; and mounting means for detachably and adjustably supporting said head in place, said mounting means comprising a band which surrounds the flexible tube and binds it on the faucet, an arm pivoted to said band, a binding screw for holding the band on the faucet and for holding the arm in the position to which it 125

130

is adjusted around said pivot, a second band which connects the flexible tube to said head and to which said arm is pivoted, and a binding screw for holding said second band on the head and for holding the head in the position to which it may be adjusted around the pivot which connects the head and arm.

Copies of this patent may be obtained for five cents each, by addressing the "Commissioner of Patents, Washington, D. C."

Signed at the borough of Brooklyn, county of Kings, city and State of New York, this 28th day of March, 1917.

WILLIAM ROSE.
